[57] CLAIM

The ornamental design for a fluorescent desk lamp, as shown and described.

DESCRIPTION

FIG. 1 is a front elevation of a fluorescent desk lamp
showing my new design;

FIG. 2 is a right side elevation thereof;

FIG. 3 is a top plan view thereof;

FIG. 4 is a rear elevation thereof;

FIG. 5 is a bottom plan view thereof; and

FIG. 6 is an enlarged cross-section thereof taken on the line VI—VI of FIG. 1, the fluorescent lamp being shown in broken lines for illustrative purposes only.
